CLAIM

I claim the ornamental design for an ionic pillar lamp, as shown and described.

DESCRIPTION

FIG. 1 is a front elevation view of the ionic pillar lamp showing my novel design;

FIG. 2 is a rear elevation view thereof;

FIG. 3 is a left side view thereof;

FIG. 4 is a right side view thereof;

FIG. 5 is a top plan view thereof; and,

FIG. 6 is a bottom plan view thereof.

The broken lines showing in all figures are for illustrative purposes only and form no part of the claimed design.
